UNITED STATES PATENT OFFICE

1,924,411

WINDOW VENTILATOR

Julius G. Moser, San Francisco, Calif.

Application December 2, 1929. Serial No. 410,989

1 Claim. (Cl. 98—99)

This invention relates particularly to a ventilator to be mounted on the outside of a window opening having a sliding sash therein to function as a protective baffle over the opening resulting when the window sash is raised into the open position, permitting the free circulation of air thru the ventilator and window opening into the area to be ventilated and preventing rain, water, dust and the like from accompanying the air flow.

An object of the invention is to provide a ventilator having a substantially triangular cross section fastened on the outside of a window frame and in engagement with the lowermost sliding sash in the frame, whereby the top side of the ventilator lies at an inclined angle to the sash to shed and deflect rain or other inclement weather away from the perforated bottom of the ventilator which lies directly below, thus permitting air to flow up thru the open bottom of the ventilator; the top side of the ventilator having an edge that lies contiguous to the sliding sash and said edge is covered by a resilient edging that wipes on the outer face of the sliding sash and effects a relatively tight sealed contact therewith to exclude rain and inclement weather from passing between the edging and the face of the sash.

Other objects and advantages are to provide a window ventilator that will be superior in point of simplicity, inexpensiveness of construction, positiveness of operation, and facility and convenience in use and general efficiency.

In this specification and the annexed drawing, the invention is illustrated in the form considered to be the best, but it is to be understood that the invention is not limited to such form, because it may be embodied in other forms; and it is also to be understood that in and by the claim following the description, it is desired to cover the invention in whatsoever form it may be embodied.

In the accompanying one sheet of drawing:

Fig. 1 is a front elevation of a fragmentary portion of a window frame having a ventilator constructed in accordance with my invention, mounted thereon.

Fig. 2 is a vertical cross section taken thru Fig. 1 on the line 2—2.

Fig. 3 is an enlarged cross section taken thru Fig. 2 on the line 3—3.

Fig. 4 is an enlarged cross section taken thru Fig. 2 on the line 4—4.

In detail the construction illustrated in the drawing comprises a framed window opening consisting of the sill 1, side jambs 2 with the parting

beads 3 and stops 4 thereon, the sash 5 slideable between the bead 3 and stops 4, and the overhead lintel, not shown. The structure described is commonly known as a "double hung" sliding window. This type of window has the sashes slideable in a vertical plane whereby when the sashes are in the opened position, an opening is formed between the top edge of the upper sash and the lintel, and an opening formed between the bottom edge of the lower sash and the sill. Thru either of the openings, or one of them, air can enter the room to be ventilated and likewise rain, dust or the like, may enter, to possibly damage furnishings, curtains and drapes within the room. My invention contemplates a ventilator 6 which may be mounted on the outside of a window frame near the bottom sash 5, whereby said sash may be opened for ventilating purposes and all air that passes thru the opened window must first pass thru the ventilator. The ventilator is so constructed and so positioned on the window frame in relation to the open sash, that air can pass freely thru the ventilator but rain, dust and the like will be excluded.

The ventilator 6 consists of a pair of end pieces 7 and 8, made of metal, wood or the like, each being formed as a right angle triangle. The inner side of the hypotenuse of each triangular end piece is provided with a guideway 9 therealong. The end pieces 7 and 8 are adapted to be either fixedly or detachably secured to the side jambs of the window frame with the hypotenuse 10 of said pieces positioned at an inclined angle to the face of the sash, thus positioning the bottom edge 11 of said pieces at a right angle to the sash face and the remaining edge 12 of said pieces substantially parallel with the sash face. There is sufficient clearance between the edge 12 of said end pieces and the sash to permit the sash 5 to be opened and closed at will.

A sheet 13 of glass, or wood, or other imperforate material is adapted to have its opposite ends slidably confined in the guideways 9 on each of the opposite end pieces 7 and 8. The sheet 13 is thus positioned at a slant angle to the sash face and the edge 14 of the sheet 13 next the sash face has a resilient edging 15 secured thereto to have a wiping contact with the outer face of the side stiles and glass forming the sash 5. The edging 15 is shaped to snugly engage the outer contour of the sash to prevent water, dirt and the like striking either the sash face or the sheet 13 from passing between the edging 15 and the sash face and hence working into the in-

rior of the ventilator and thru the opened window. The edging 15 is preferably formed of sheet rubber secured to the edge of the sheet 13 by a pressed metal clip 16.

5 The bottom edges 12 of the end pieces 7 and 8 and the bottom edge 17 of the upper sheet 13 are enclosed by a perforated frame 18, formed of screen or the like. The screen 18 lies above and extends out beyond the window frame sill 1, 10 so that air entering the ventilator comes up from underneath. The sheet 13 covers the screened bottom of the ventilator and prevents anything striking the ventilator from above from entering the ventilator.

15 When the lower edge of the sash 5 is raised away from the sill 1, to a point opposite the upper edge 14 of the deflecting sheet 13, an opening is provided thru the window frame, corresponding in area to that of the screen 18, thru which air 20 from the ventilator can flow. The air entering the ventilator from the bottom will be freed of rain, dust, or the like, and hence will exclude therefrom those things which might do possible damage to the curtains and furnishings.

It is to be understood that the ventilator may be installed in a window frame as a complete unit or it may be installed piece-by-piece out of the separate elements of which it is made up.

Having thus described this invention, what I claim and desire to secure by Letters Patent is:

In a window ventilator for sliding windows, said ventilator having a housing of substantially triangular cross section secured at its opposite ends to the window jambs, the base of the triangular housing being perforated and arranged at right angles opposite the lower end of the window, the side of the housing adjacent the window being open, and the inclined side of the housing being imperforate and being extended from the outer edge of said base upwardly toward the window, a clip on the longitudinal edge of the inclined imperforate side of the ventilator extended alongside the window, and a resilient rubber edging fixedly secured in said longitudinal clip to be resiliently pressed against the sliding window at the top of the ventilator.

JULIUS G. MOSER.
